(57) **CLAIM**

The ornamental design for an interchangeable lens for camera, as shown and described.

DESCRIPTION

FIG. 1 is a front view of the interchangeable lens for camera showing the first embodiment our new design;

FIG. 2 is a rear view thereof;

FIG. 3 is a plan view thereof;

FIG. 4 is a right side view thereof;

FIG. 5 is a front perspective view thereof;

FIG. 6 is a front view thereof, showing the diaphragm adjuster in a transition state;

FIG. 7 is a front view thereof, showing the diaphragm adjuster in a full opening state;

FIG. 8 is a reference 8-8 end view thereof with an internal mechanism omitted;

FIG. 9 is an enlarged front perspective view of the diaphragm adjuster;

FIG. 10 is a front view of the interchangeable lens for camera showing the second embodiment our new design;

FIG. 11 is a rear view thereof;

FIG. 12 is a plan view thereof;

FIG. 13 is a right side view thereof;

FIG. 14 is a front perspective view;

FIG. 15 is a front view thereof, showing the diaphragm adjuster in a transition state;

FIG. 16 is a front view thereof, showing the diaphragm adjuster in a full opening state;

FIG. 17 is a reference 17-17 end view thereof with an internal mechanism omitted; and,

FIG. 18 is an enlarged front perspective view of the diaphragm adjuster.

The broken lines depict environmental subject matter only and form no part of the claimed design.
